UNITED STATES PATENT OFFICE

DE WITT TALMADGE MOATS, OF COLUMBUS, OHIO, ASSIGNOR TO THE D. L. AULD COMPANY, OF COLUMBUS, OHIO

STENCILING MACHINE

Application filed April 12, 1930. Serial No. 443,848.

The present invention is directed to improvements in stenciling machines for applying enamel to name plates for automobiles, but it will be of course understood that it is not limited to such use since it can be used for applying enamel to plates for other uses.

The primary object of the invention is to provide a device of this character so constructed that the stencil plate for applying the enamel to the name plate or the like can be quickly placed upon the plate being decorated or enameled and removed therefrom after the application of the enamel, and in such manner that the hands of the operator may both remain free in order that the plates can be successively placed in position for receiving enamel through the stencil plate when the same is positioned on the plate.

Another and important object of the invention is to provide novel means for imparting to the stencil plate vibration previous to the lifting of the same from the plate being enameled to cause dislodgement of enamel from the slots or traceries of the stencil plate.

Another object of the invention is to provide a device of this kind so constructed that a large range of adjustments can be made to permit the use of stencil plates of various sizes.

Another object of the invention is to provide a device of this type so constructed that the stencil plates can be easily and quickly interchanged.

Another object of the invention is to provide a device of this character constructed in such manner that the stencil plates have smooth and unobstructed upper surfaces to permit the use of a blade spreader.

Another object of the invention is to provide a machine of this kind including a swinging frame so constructed that the stencil plate after once being attached to the frame can be used without the necessity of holding the same by hand, thereby preventing dropping the same due to careless handling. Obviously when a stencil plate is carelessly handled and dropped the same becomes damaged and worthless, therefore a machine constructed in accordance with my

invention not only promotes production, but eliminates unnecessary replacement of stencil plates.

With these and other objects in view, this invention resides in the novel features of construction, formation, combination and arrangements of parts to be hereinafter more fully described, claimed and illustrated in the accompanying drawings, in which:

Figure 1 is a perspective view showing the stencil plate in a partly elevated position.

Figure 2 is a similar view showing the stencil plate in its operative position.

Figure 3 is a side elevation.

Figure 4 is a detail view, showing the detent and arm in the position assumed when the stencil plate is resting upon the name plate.

Figure 5 is a detail view showing the position of the detent just previous to the release of the hammer.

Figure 6 is a detail view showing the position of the detent after release of the hammer.

Figure 7 is a transverse detail sectional view through the stencil plate and name plate.

Figure 8 is an enlarged perspective view of one of the clamps.

Figure 9 is a fragmentary perspective view showing the stencil plate trunnion and slot of one arm.

Referring to the drawings, 1 designates a base which may be secured by bolts or screws 2 to a work bench or other support 3. Mounted upon the base adjacent the ends thereof are bearing blocks 4-4 in which are journaled the ends of the rod 5 of the frame 6. The frame 6 further consists of side bars 7-7 and parallel spaced rods 8 and 9, the ends of which being fixed in the bars 7-7. It will be observed that the rod 5 constitutes a pivotal connection for the frame 6.

A pair of stencil supporting arms 10 are employed, which are slidably adjustable upon the rods 5, 8 and 9, said arms being held in selected adjusted positions through the medium of the clamps 11 carried by the rods 5 and 9. By the provisions of the clamps 11 the arms 10 may be conveniently adjusted laterally to accommodate stencil plates 12 of various sizes.

The stencil plate has formed upon its ends

blocks 13 having trunnions 14 carried thereby, said trunnions being passable through slots 15 formed in the ends of the arms 10. The slots open into circular openings 16, and 5 since the trunnions 14 are substantially rectangular in cross section they may be passed freely through the slots 15 when the plate is in angular relation with respect to the arms. After the trunnions enter the openings 16 the 10 plate is turned to lie in a plane with the arms 10, thus connecting the plate and arms.

The stencil plate is provided with slots 17 of a selected design and is further provided with a bottom recess 18 for receiving the name 15 plates 19. The name plates 19 are formed with recesses 20 corresponding to the configuration of the slots 17 of the stencil plate so that when the stencil plate is resting upon the name plate the slots thereof will register 20 with the recesses of the name plate.

Having its inner end suitably fixed to the base 1 is a bar 21 upon the outer end of which is clamped a rest 22 upon which the name plates 19 are adapted to rest. The rest 22 may 25 be adjusted longitudinally of the bar 21 through the medium of the clamping blocks 23. The rest carries studs 24 to positively position the name plate thereon.

Fixed to the rod 5 is an arm 25 which is 30 pivotally connected to the bell crank lever 26 by a link 27, said lever being pivotally connected to the bracket 28 secured to the bench 2. The bell crank lever has pivotally connected thereto a rod 29 connected in any suitable manner to a pedal, not shown, for operation 35 by the foot of the operator.

The arm 25 has carried thereby a bolt 30 and to which are pivotally connected the links 31, one upon each side of said arm and normally maintained in spaced relation thereby. These links are formed with hooks 32 and seats 33 provided by slotting the links. The 40 links are capable of sliding upon the rod 8 so that the hooks and seats will alternately engage said rod, the purpose of which will appear later.

Also pivotally connected to the bolt 30 is a 45 detent 34 having hook 35 upon its free end, which is rounded, as at 36. Pivotally mounted on the rod 8 is a head 37, there being a coil 50 spring 38 connecting the detent and head. The head has carried thereby a shaft 39, upon the outer end of which is mounted a hammer 40, in the form of a ball, said hammer 55 being so located that the impact of its blow will be imparted to the rod 9 of the frame to transmit thereto a shock, which is also transmitted to the stencil plate and at a time just 60 previous to it being lifted from the name plate 19. Obviously the recess 18 of the stencil plate will positively hold the same upon the rest 22 while the enamel is being applied.

Briefly the operation is as follows:

To rock the frame 6 upwardly and permit 65 the operator to place a name plate upon the

rest 22 it is only necessary to actuate the link 29, either by foot or in any other suitable way. As the frame swings upwardly the stencil plate is lifted therewith in order that the plate can be conveniently placed 70 upon the rest. Movement of the link rocks the bell crank lever 26 and as the arm 25 swings rearwardly the links 31 slide upwardly until the hooks 32 thereof grasp the rod 8, whereupon the frame and arms 10 are lifted, 75 thus elevating the stencil plate so that the rest 22 is readily accessible. The arm 25 is then swung forwardly to permit the frame to swing downwardly until the parts are again in the position as shown in Figure 4. The 80 enamel is then applied to the stencil plate and enters the corresponding recesses of the name plate with which register the slots of said stencil plate.

Owing to the fact that the upper surface 85 of the stencil plate is smooth and unobstructed a suitable blade or stylus may be conveniently slid thereover to force the enamel through the slots into the recesses of the name plate. After the application of the 90 enamel the bell crank lever is rocked reverse- 95 ly, whereupon the arm 25 swings rearwardly and takes with it the detent 34, the hook 35 of which is now engaged with the head 37. As the arm 25 continues to swing rearwardly 100 the detent rocks the head 37 and lifts the shaft 39, and thus the hammer 40, and at which time the spring 38 is under tension. In Figure 5 the hook 35 is shown in a position just previous to it disengaging the head 105 37, and at which time the hooks 32 of the links are about to grasp the rod 8 so that the frame 6 will be swung upwardly to lift the stencil plate 12, and just previous to the 110 engagement of the hooks 32 with the rod 8 the hook 35 of the detent rides from engagement with head 37, whereupon the spring 38 115 now acts to swing the shaft 39 and the hammer 40 downwardly in order that the hammer 120 will sharply strike the rod 9, thus vibrating the frame 6 to such an extent that any enamel remaining in the slots of the 125 stencil plate will be dislodged therefrom, and prior to the lifting of the stencil plate from the name plate occupying the rest 22. Further rearward swinging of the arm swings the frame 6 upwardly since the hooks 32 are now engaged with the rod 8 of said frame. The name plate can now be lifted from the rest 22 and a new one placed thereon. After 130 placing a new name plate upon the rest 22 the arm 25 is swung forwardly, thus swinging the frame 6 downwardly, and at which time the detent 34 is in the position as shown 135 in Figures 3 and 6. It will be noted that when the stencil plate is resting upon the name plate the latter will be held firmly upon the rest 22. When the stencil plate rests upon the name plate the movement of the frame is arrested, but the arm 25 continues 140

to swing forwardly from the position assumed in Figure 6 to the position as shown in Figure 4. When the seats 33 of the links engage the rod 8 the hook 35 drops into engagement with the head 37, the rounded surface 36 of the hook riding easily over the similar surface 41 of the head. When the hook 35 is again in this position operation of the bell crank lever and consequent swinging 10 of the arm 25 will again actuate the hammer 40 prior to the lifting of the frame and stencil plate.

Since the seats 33 of the links 31 engage the rod 8 swinging of the arm 25 in a forward direction is limited, but not before the hook 35 can drop into interlocking engagement with the head 37.

It will thus be seen that the stencil plate can be lifted and lowered in such manner 20 that both hands of the operator may be free, and that it will not be necessary to handle the stencil plates except when interchanging the same.

A tray 42 may be suitably secured to the bench 2 under the rest 22 so that surplus enamel which may drop during the operation 25 of the machine may be collected.

Since the arms 10 may be adjusted laterally upon the rods of the frame stencil plates 30 varying in size may be used, and since the stencil plates are all provided with similar trunnions 14, they can be easily and quickly removed and replaced in the slots 15 and openings 16 of the arms 10 upon merely swinging the plates in angular relation with the arms or in a plane therewith, according 35 to the option of the operator.

What is claimed is:—

1. The combination with a rest for supporting a plate having recesses therein for receiving enamel, of a stencil, means for swinging the stencil for engagement on the plate for placing the slots thereof in registration with the recesses of the plate to permit passage of enamel through the slots of the stencil into the recesses of the plate, means for swinging the frame upwardly, and means operable for swinging the stencil away from the plate to subject the frame to vibration previous to disengagement of the stencil from the plate.

2. The combination with a base, of a frame pivotally connected therewith including rods, a rest supported by the base, a pair of arms slidably adjustable on the rods, a stencil detachably connected with the arms, means for swinging the frame to lift or lower the arms, and thus the stencil to alternately place and remove the same from engagement with a plate resting upon said rest, as and for the purpose set forth.

3. The combination with a base, of a frame pivotally connected therewith, a pair of arms slidably adjustable on the frame, said arms having slots in their free ends, a stencil hav-

ing trunnions carried thereby for detachable engagement in said slots, a head fixed to one bar of the frame and having a hammer connected therewith, an arm fixed to the frame, a detent carried by the arm for engaging the head to actuate the hammer for striking the frame to impart vibration to the frame, and thus the stencil before the frame has completed its swinging movement in one direction, as and for the purpose set forth. 70 75

4. The combination with a base, of a frame pivotally connected therewith, arms carried by the frame, a stencil detachably connected with the arms, a rest supported by the frame for supporting a plate to receive enamel 80 forced through the slots of the stencil when resting upon the plate, an arm fixed to the frame, a detent pivotally connected with the arm, a head fixed to the frame, a hammer supported by the head, links pivotally carried 85 by the arm and slidably engaged with a rod of the frame, said head being adapted to engage the detent when the stencil is resting upon the plate and to disengage the detent when the frame is swung upwardly and at a 90 time before the stencil is lifted from the plate to release the head to permit the hammer to strike the frame and impart vibration thereto, and to the stencil, said links serving to complete the upward swinging movement of the frame upon actuation of the arm, 95 and means for actuating the arm.

5. The combination with a base, of a frame pivotally connected thereto, a stencil swingable with the frame, an arm fixed to the frame, a detent pivotally connected to the arm, a head fixed to the frame, a hammer carried by the head, said stencil when resting upon the plate permitting the passage of enamel through the slots thereof for application to the plate, means for swinging the arm to actuate detent to swing the head rearwardly to operate the hammer upon disengagement of the detent and head, whereby the hammer is released to strike the frame 100 105 110 to impart vibration thereto before the frame swings to a position for lifting the stencil from the plate.

In testimony whereof I affix my signature.

DE WITT TALMADGE MOATS.
